BLIND STITCH SEWING MACHINE

Louis G. Bowman, St. Louis, Mo., assignor to
 Lewis Invisible Stitch Machine Company, St.
 Louis, Mo., a corporation of Maine

Application December 28, 1936, Serial No. 117,940

34 Claims. (Cl. 112—176)

This invention relates to new and useful improvements in blind stitch sewing machines generally, although more particularly to blind stitch machines of the single thread chain stitch type adapted especially for hemming operations.

It is a well known fact that if the last formed needle thread loop in the stitched seam is not locked, the entire line of stitches may be pulled out accidentally.

10 Among the several objects of my invention are to provide means for severing the thread whereby when the seamed article is removed from the machine the last formed needle loop in the seam will be locked by the trailing end of the thread; 15 to provide such severing means which will also function to pull off thread from the supply; to provide a clamp for clamping the supply end of the thread adjacent the point of severance whereby when the machine is again operated the 20 stitch forming mechanism will immediately function, and to provide means for operating the thread severing means upon depression of the work support.

With these and other objects in view which 25 will more fully appear, the nature of the invention will be more clearly understood by following the description, the appended claims, and the several views illustrated in the accompanying drawings.

30 In the drawings—

Figure 1 is a front elevation of a blind stitch sewing machine embodying my invention,

Figure 2 is a top plan view thereof,

Figure 3 is an enlarged section showing the 35 thread carrier and the actuating means therefor in their normal positions,

Figure 4 is a similar view but showing the thread carrier and the actuating means therefor in their operative positions,

40 Figure 5 is an enlarged detail plan view showing the presser foot, the needle, the looper, the stitched fabric, and the thread carrier,

Figure 6 is a plan view of the completed seam showing the last formed needle thread loop 45 locked by the trailing end of the thread,

Figures 7, 8 and 9 are views of the thread clamp and stationary knife, and

Figure 10 is a perspective view of the thread carrier.

50 Like reference numerals designate corresponding parts throughout the several figures of the drawings.

My invention is adapted especially for joining a hem A to a body fabric B by a line of blind 55 stitches of the single thread chain stitch type, as

shown in Figure 6. A needle thread C is employed to form the stitches and the needle loops c are spaced equidistantly apart, and the connecting portions of the thread between the loops are arranged in a straight line and in parallelism 5 to the inner edge a of the hem.

The machine to which my invention is applied is disclosed in Patent 2,030,751, issued to Joseph Mann on Feb. 11, 1936, and includes a main frame comprising a base 5 having a standard 6 10 projecting from the rear right hand corner thereof, an arm 7 which extends laterally from the upper end of the standard, and an arm 8 which extends forwardly from the left hand end of the arm 7. Fixed to the free end of the arm 8 is a 15 horizontal presser foot 9 having a centrally located and longitudinally extending opening 10 therein. The foot is attached at its rear end to the arm by a screw 11, and the front portion of the foot is held against flexing by spaced posts 20 12, 13 which are connected to the opposite sides of the foot and to the arm. Journaled in the arm 7 of the frame is a main shaft 14, the left hand end thereof projecting across the rear end of the arm 8. Journaled in the arm 8 and extending 25 longitudinally thereof is an oscillatory needle shaft 15 which is driven from the main shaft by the usual connections. The needle shaft 15 is disposed directly above the opening 10 in the foot, and fixed to the outer end of the shaft is a 30 needle arm 16 carrying a curved needle 17. Thus when the needle shaft is oscillated the needle will reciprocate transversely across and above the opening 10 in the presser foot. It will be noted that the penetrating stroke of the needle, as 35 viewed from the front of the machine, is from right to left. Rigid with the base 5 are posts 18 which are located in a plane in advance of the standard 6 and a work support 19 is pivotally supported as at 19a on the upper ends of these 40 posts and includes a lateral extension 20 which projects under the presser foot 9, and an arm 19b which projects rearwardly beyond the pivot 19a, the work support being yieldably held against depression by a spring 21. An adjustable screw 19c is threaded into the rearwardly extending arm 19b for engagement with a part 45 of the machine frame for variably limiting the upward movement of the work support. A reciprocating ridge forming element R which in 50 the present machine is shown as a disc, is provided for projecting nodes of fabrics upwardly through the opening 10 in the foot into needle penetrating position. This disc R is fixed to a rock shaft 22 journaled on the underside of the 55

work support 19 and oscillated in timed relation with the needle reciprocations from the main shaft by connections indicated as a whole by the numeral 23. Vertically yieldable work clamps 24, 24 are mounted on the work support and are located on opposite sides of the disc R, the rear portions of the clamps in rear of the needle path being disposed in close relation directly under the opening 10 in the foot. A top feed dog 25 is mounted on a feed bar 26 which extends longitudinally within the frame arm 8 and is operated in the usual manner from the main shaft 14. In order to form the line of single thread chain stitches, I employ a complementary stitch forming mechanism which cooperates with the needle 17 and includes a loop taker X. This loop taker is in the form of a non-thread carrying looper having an arcuate beak 27 and an attaching shank 28, the latter being secured to a holder 29 by a clamp screw 30. The holder 29 is clamped by a screw 31 to the lower end of a vertically disposed rock shaft 32 which is journaled in a bracket 33 attached to the forward end of the frame arm 8 by screws 34, the shaft 32 and the loop taker X being located above the presser foot 9 and at the left of the opening 10 therein. The shaft 32 is also disposed in front of the vertical plane containing the path of needle reciprocations. The beak 27 of the loop taker extends rearwardly relative to the shank 28 and oscillates in a horizontal plane above the needle 18. The inner edge 35 of the loop taker is concentric to the axis of the shaft 32. Fixed to the upper end of the looper shaft 32 is a rearwardly extending rock arm 36 and pivotally connected to the rear end thereof is one end of a link 37, the other end of said link being connected to the upper end of a rock arm 38 fixed to the needle shaft 15. Fixed to the presser foot 9 by a screw 39 is a thread loop abutment 40 which is located intermediate the looper X and the left hand wall of the opening 10, and the forward end 41 of the abutment being located at a point slightly in rear of the vertical plane containing the path of needle travel.

In operation of the machine as thus far described, the machine is loaded in the usual manner by first depressing the work support 19 and inserting the body fabric A and hem B under the presser foot 9, the body fabric extending to the left of the hem, whereby the needle 18 will enter the hem and have its penetrating or forward movement towards the inner edge of the hem. The needle after passing through the hem will then enter and emerge from the upper face of the body fabric at a point under the hem and in spaced relation to the inner edge thereof. As the needle begins to recede, it casts out the usual needle thread loop and the beak of the looper will then enter said loop. As soon as the needle point is withdrawn from the hem, the fabric will be fed rearwardly a stitch length distance, and during this time the looper will complete its rearward or loop taking movement and the needle loop which is around the looper will be fed rearwardly against the forward end 41 of the abutment 40 which functions to maintain the needle loop in open relation and in the proper position to be entered by the needle on its next forward stroke.

As previously stated, my invention is applied to the above described blind stitch machine, and functions (1) to cut the leg c¹ of the needle thread C whereby when the work support is depressed and the hemmed fabric is withdrawn from the

machine, the trailing end of the thread will remain within the needle thread loop of the last formed stitch to thereby lock the formed stitches against accidental raveling, (2) to pull off thread from the supply in order to insure the formation of stitches immediately upon the beginning of the next stitching operation, and (3) to clamp the supply thread at the cut end thereof until two or more stitches have been formed in said next stitching operation.

To this end, I have provided a thread cutting mechanism which includes a stationary knife D and a cooperating movable thread carrier E which are located above the presser foot 9. The knife D is formed from a thin strip of metal and includes an attaching arm 42 and a blade 43 arranged in planes at right angles to each other, the lower edge of the blade being sharpened as indicated at 44. The arm 42 is located immediately in rear of the vertical plane containing the path of travel of the needle, and is secured to the attaching arm 45 of a thread clamp F by a screw 46, and the attaching arm 45 is secured to the front end of the frame arm 8 by screws 47, the blade 43 extending rearwardly and being located at the right of the presser foot opening 10, and the sharpened edge 44 being located above and in spaced relation to the foot.

The thread clamp or nippers F includes a downwardly extending and relatively rigid front arm 48 which is preferably integral with the attaching arm 45, and a relatively flexible rear arm 49 disposed in rear of and in parallelism with the front arm 48 and secured at its upper end thereto by a screw 50. The lower end of the front arm is curved forwardly as at 51 and cooperates with the lower end of the rear arm 49 to form a resultant thread receiving throat 52 which is located at the right of the presser foot opening 10 and directly above the leg c¹ of the needle C which is around the looper X when the needle is at the rear end of its stroke.

The thread carrier E is mounted on the presser foot and is movable upwardly to engage the leg c¹ of the thread and elevate the same into the thread clamp F and then into cutting cooperation with the knife D, whereby (1) thread will be pulled from the supply, (2) the supply end of the leg c¹ of the thread will be clamped, and (3) the leg c¹ will be severed. The thread carrier E comprises a rock arm 53 which is preferably constructed integral with a rock shaft 54, and the outer end of the arm is forked to form resultant spaced thread supporting arms 55, 55 and an inwardly extending slot 56 therebetween, the upper faces of the arms adjacent their outer ends being provided with recesses or seats 57, 57, and the slot being disposed in vertical alinement with the blade 43 of the stationary knife D.

A horizontal bearing plate 58 is attached by screws 59 to the upper face of the presser foot on the right hand side of the opening 10 and in rear of the path of movement of the needle. The plate is provided with spaced transverse bearings 60, 61 in which the rock shaft 54 is journaled. The right hand end of the rock shaft projects beyond the bracket 58 and fixed thereon is a hub 62 which contacts the right hand bearing 60 and has a rearwardly extending rock arm 63 rigid therewith. A collar 64 is fixed to the rock arm 54 and contacts the left hand bearing 61. Thus the hub 62 and collar 64 cooperate with the bearings 60, 61 to maintain the rock arm 53 of the thread carrier E against lateral movement. The rock arm 53 extends forwardly from the

rock shaft 54, and is normally positioned in a longitudinally extending slot 65 formed in the presser foot 9 on the right of the slot 10 therein. A coil spring 66 has one end connected to an 5 upwardly extending rock arm 67 fixed to the rock shaft 54 intermediate the bearings 60, 61 and has its other end fixed to an anchor plate 68 attached to the right hand post 13 of the presser foot. The spring functions to yieldably retain 10 the thread carrier arm 53 in its normal position within the slot 65, the downward movement of the arm being stopped by the arm contacting the foot at the rear end of the slot. Thus, when the rock arm 63 is depressed, the thread carrier 15 arm 53 will be elevated against the tension of the spring 66, and the carrier arms 55, 55 will be positioned on opposite sides of the blade 43 of the stationary knife D.

It is desirable to actuate the thread carrier E 20 immediately prior to the stitched article being removed from the machine in order to effect a locking of the needle loop of the last formed stitch. To this end, I have provided means for actuating the carrier E upon depression of the 25 work support. For this purpose, a vertical arm 69 is rigidly connected to the left side of the rearwardly extending arm 19b of the work support and at a point adjacent the lateral arm 7 of the main frame. A horizontal arm 70 which is 30 fixed to the upper end of the arm 69, is disposed in parallelism with the lateral arm 7 and terminates at its free end in spaced relation to the forwardly extending frame arm 8 at a point in rear of the rock arm 63. A bearing arm 71 is 35 attached to the frame arm 8 intermediate the horizontal arm 70 and the rock arm 63, and a lever 72 extends in parallelism with the frame arm 8 and is fulcrumed intermediate its ends as at 73 on said bearing arm 71. The forward 40 end of the lever 72 carries a laterally extending pin 74 which overlies the rock arm 63 and the rear end of the lever overlies the free end of the horizontal arm 70. The lower rear edge of the lever is cut away as at 75 to permit the arm 70 45 to continue its forward and upward movement after the thread carrier arm 53 has been elevated to its operative position with respect to the stationary knife D, without imparting unnecessary additional movement to said thread carrier arm, 50 as shown in Figure 4.

In operation, after a hem has been seamed, the machine is stopped with the needle at the beginning of its stroke, the work support 19 is then depressed by a treadle or knee-press which 55 is connected thereto in the usual manner, and the seamed hem is then withdrawn from the machine. During the depression movement of the work support, the horizontal arm 70 which is mounted on the rear extension 19b thereof, is elevated and raises the rear end of the lever 72 which is fulcrumed on the frame arm 8. The 60 downward movement of the front end of the lever swings the rock arm 63 downwardly and this effects the elevation of the thread carrier arm 65 65 to raise the leg c¹ of the needle thread loop which is around the looper into the throat 52 and then between the clamping or nipping arms 48, 49 of the thread clamp F. The carrier arm 53 moves upwardly between the looper and the 70 thread clamp F, and after the thread has been nipped by the clamp, it is moved upwardly into cooperative relation with the stationary knife and there severed. It will be observed that a long length of trailing thread is thus privided where- 75 by when the stitched hem is withdrawn from the

machine, the last formed needle loop will be locked and the length of said trailing thread will suffice to prevent the same from being accidentally withdrawn from said loop. After the thread has been thus severed, the supply end of the thread will remain in the clamp F until after at least two stitches have been formed in the next stitching operation, the retention of this supply end of the thread by the clamp insuring the formation of a stitch during the first forward 10 travel of the needle.

It will be also observed that inasmuch as the thread supply is anchored by reason of the needle thread loop extending around the looper, the upward movement of the carrier arm 53 will pull 15 off from the supply a sufficient amount of thread which will be retained by the thread clamp until two or more stitches have been formed in the next seaming operation.

It is of course to be understood that the details of structure and arrangement of parts may be variously changed and modified without departing from the spirit and scope of my invention.

I claim:

1. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, and means located between the looper 30 and the needle when the latter is at the beginning of its forward stroke to sever the leg of the needle thread loop extending around the looper.

2. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, a stationary knife located above the foot and between the looper and the needle 40 when the latter is at the beginning of its stroke, and a manually operable carrier for raising the leg of the needle loop extending around the looper into cooperative cutting relation with said knife.

3. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, a stationary knife located above the foot and between the looper and the needle when the latter is at the beginning of its stroke, and a manually operable carrier for raising the leg of the needle loop extending around the looper into cooperative cutting relation with said knife, 55 said carrier comprising an arm fulcrumed on the presser foot in rear of the needle path and having its forward end normally disposed under said leg of said needle loop, the free end of the arm being slotted to form resultant thread sup- 60 65 70 75

porting arms movable to opposite sides of the knife.

4. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element

5 for projecting a ridge of fabric upwardly through the opening into needle penetrating position, a stationary knife located above the foot and between the looper and the needle when the latter is at the beginning of its stroke, and

10 a manually operable carrier for raising the leg of the needle loop extending around the looper into cooperative cutting relation with said knife, said carrier comprising an arm fulcrumed on the presser foot in rear of the needle path and having its forward end normally disposed under said leg of said needle loop, the free end of the arm being slotted to form resultant thread supporting arms movable to opposite sides of the knife, the upper faces of the arms being recessed to

15 form thread seats.

20 5. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, a stationary knife located above the foot and between the looper and the needle when the latter is at the beginning of its stroke, and

25 a manually operable carrier for raising the leg of the needle loop extending around the looper into cooperative cutting relation with said knife, said carrier comprising an arm fulcrumed on the presser foot in rear of the needle path and having its forward end normally disposed under said leg of the needle loop,

30 means for yieldably retaining the carrier arm against upward movement, and manually operable means for raising the carrier arm against the tension of said yieldable means.

35 6. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element

40 for projecting a ridge of fabric upwardly through the opening into needle penetrating position, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving

45 said thread into severing relation with said knife.

50 7. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, a

55 thread clamp located between the looper and the needle when the latter is at the beginning of its forward stroke, a thread cutting knife and means located between the thread clamp and the looper for first positioning the leg of the needle loop extending around the looper into the thread clamp and for subsequently moving said thread into severing relation with said knife, said clamp comprising vertically disposed clamping arms forming a resultant thread receiving throat at their lower end and located directly above said leg of the needle loop.

60 8. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving said thread into severing relation with said knife, said carrier comprising a carrier arm fulcrumed on the presser foot in rear of the needle path and having its forward end normally disposed under said leg of the needle loop.

65 9. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element

70 for projecting a ridge of fabric upwardly through the opening into needle penetrating position, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving said thread into severing relation with said knife, said position means comprising a carrier arm fulcrumed on the presser foot in rear of the needle path and having its forward end normally disposed under said leg of the needle loop, means for yieldably retaining the carrier arm against upward movement, and manually operable means for raising the carrier arm against the tension of said yieldable means.

75 10. In a single thread blind stitch sewing machine, the combination with a stationary presser foot having an opening therein, of a threaded needle located above the foot for reciprocatory movements across the opening thereof, a non-threaded looper located above the foot for co-operation with said needle, a ridge forming element for projecting a ridge of fabric upwardly through the opening into needle penetrating position, a thread clamp located between the looper and the needle when the latter is at the beginning of its forward stroke, a stationary knife located above the foot, and means located between the thread clamp and the looper for first positioning the leg of the needle loop extending around the looper into the thread clamp and for subsequently co-operating with the knife in severing said thread,

5 said last named means including a carrier arm fulcrumed on the presser foot in rear of the needle path and having its forward end normally disposed under said leg of the needle loop, the
 10 free end of the arm being slotted to form resultant thread supporting arms movable to opposite sides of the knife, means for yieldably retaining the carrier arm against upward movement, and manually operable means for raising the carrier arm against the tension of said yieldable means.

15 11. In a single thread blind stitch sewing machine, the combination with a stationary presser foot having an opening therein, of a threaded needle located above the foot for reciprocatory movements across the opening thereof, a non-threaded looper located above the foot for cooperation with said needle, a ridge forming element for projecting a ridge of fabric upwardly through
 20 the opening into needle penetrating position, a thread clamp located between the looper and the needle when the latter is at the beginning of its forward stroke comprising vertically disposed clamping arms forming a resultant thread
 25 receiving throat at their lower end and located directly above said leg of the needle loop, a thread cutting knife, and means located between the thread clamp and the looper for first positioning the leg of the needle loop extending around the
 30 looper into the thread clamp and for subsequently moving said thread into severing relation with said knife, said positioning means comprising a carrier arm fulcrumed on the presser foot in rear of the needle path and having its forward end normally disposed under said leg of the
 35 needle loop.

12. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the
 45 needle, and thread severing means operative above the foot and between the looper and the needle when the latter is at the beginning of its stroke.

13. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of
 50 needle penetration in the fabric for engaging the needle thread loop and holding the same for re-entrance by the needle, a stationary knife located above the foot and between the looper and the needle when the latter is at the beginning of its stroke, and a manually operable carrier arm for raising the leg of the needle loop extending around the looper into cooperative cutting relation with said knife.

14. In a single thread blind stitch sewing machine, the combination with a stationary presser

5 foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, said looper being supported for oscillatory movements about a vertical axis and including a curved beak movable in a horizontal plane, and thread severing means operative above the foot and between the looper and the needle when the latter is at the beginning of its stroke.

15. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a stationary knife located above the foot and between the looper and the needle when the latter is at the beginning of its stroke, a manually operable carrier arm for raising the leg of the needle loop extending around the looper into cooperative cutting relation with said knife, means for yieldably retaining the carrier arm against upward movement, and manually operable means for raising the carrier arm against the tension of said yieldable means.

16. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a stationary knife located above the foot and between the looper and the needle when the latter is at the beginning of its stroke, a manually operable carrier arm for raising the leg of the needle loop extending around the looper into cooperative cutting relation with said knife, the free end of the arm being slotted to form resultant thread supporting arms movable to opposite sides of the knife, means for yieldably retaining the carrier arm against upward movement, and manually operable means for raising the carrier arm against the tension of said yieldable means.

17. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle pen-

trating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving said thread into severing relation with said knife.

18. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving said thread into severing relation with said knife, said clamp comprising vertically disposed clamping arms forming a resultant thread receiving throat at their lower end and located directly above said leg of the needle loop.

19. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving said thread into severing relation with said knife, said positioning means comprising a carrier arm fulcrumed on the presser foot in rear of the needle path and having its forward end normally disposed under said leg of the needle loop.

20. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle,

a non-threaded looper located above the foot and operating entirely on the side of the ridge forming element opposite the point of needle penetration in the fabric for engaging the needle thread loop and holding the same for re-entrance by the needle, a thread clamp located between the looper and the needle when the latter is at the beginning of its forward stroke, a thread cutting knife, and means located between the thread clamp and the looper for first positioning the leg of the needle loop extending around the looper into the thread clamp and for subsequently moving said thread into severing relation with said knife, said positioning means comprising a carrier arm fulcrumed on the presser foot in rear of the needle path and having its forward end normally disposed under said leg of the needle loop, means for yieldably retaining the carrier arm against upward movement, and manually operable means for raising the carrier arm against the tension of said yieldable means.

21. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a thread clamp located between the looper and the needle when the latter is at the beginning of its forward stroke, a stationary knife located above the foot, and means located between the thread clamp and the looper for first positioning the leg of the needle loop extending around the looper into the thread clamp and for subsequently cooperating with the knife in severing said thread, said last named means comprising a carrier arm fulcrumed on the presser foot in rear of the needle path and having its forward end normally disposed under said leg of the needle loop, the free end of the arm being slotted to form resultant thread supporting arms movable to opposite sides of the knife, means for yieldably retaining the carrier arm against upward movement, and manually operable means for raising the carrier arm against the tension of said yieldable means.

22. In a single thread blind stitch sewing machine, the combination with a stationary presser foot having an opening, a threaded needle located above the foot for reciprocations transversely across the presser foot opening, a ridge forming element for projecting a ridge of fabric upwardly through the opening into needle penetrating position, means for feeding the fabric to the needle, a non-threaded looper located above the foot and operating entirely on the side of the ridge forming element opposite the point of needle penetration in the fabric for engaging the needle thread loop and holding the same for re-entrance by the needle, a thread clamp located between the looper and the needle when the latter is at the beginning of its forward stroke comprising vertically disposed clamping arms forming a resultant thread receiving throat at their lower end and located directly above said leg of the needle loop, a thread cutting knife, and means located between the thread clamp and the looper for first positioning the leg of the needle loop extending

- around the looper into the thread clamp and for subsequently moving said thread into severing relation with said knife, said positioning means comprising a carrier arm fulcrumed on the 5 presser foot in rear of the needle path and having its forward end normally disposed under said leg of the needle loop.
23. In a blind stitch sewing machine, the combination with a frame, of a stationary presser 10 foot mounted on said frame and having an opening therein, a stitch forming mechanism mounted on the frame above the foot and including a threaded needle mounted for reciprocations across the opening in said foot, a depressible 15 work support mounted on the frame below the foot, a ridge forming element mounted on the work support for projecting a ridge of fabric upwardly through the opening into needle penetrating position, normally inoperative means for 20 severing the needle thread above the foot, and means for rendering the severing means effective upon depression of the work support.
24. In a blind stitch sewing machine, the combination with a frame, of a stationary presser foot 25 mounted on said frame and having an opening therein, a stitch forming mechanism mounted on the frame above the foot and including a threaded needle mounted for reciprocations across the opening in said foot, and a cooperating loop taker, 30 a depressible work support mounted on the frame below the foot, a ridge forming element mounted on the work support for projecting a ridge of fabric upwardly through the opening into needle penetrating position, a thread clamp located between 35 the loop taker and the needle when the latter is at the beginning of its stroke, a thread cutting knife, normally inoperative means for first positioning the leg of the needle thread extending from the needle into the thread clamp and for 40 subsequently moving said thread into severing relation with said knife at a point between the clamp and the fabric being stitched, and means for rendering said positioning and severing means effective upon depression of the work support.
25. In a single thread blind stitch sewing machine, the combination with a frame, of a stationary presser foot mounted on said frame and having an opening therein, a stitch forming mechanism mounted on the frame above the foot and 45 including a threaded needle mounted for reciprocations across the opening in said foot and a cooperating non-threaded looper, a depressible work support mounted on the frame below the foot, a ridge forming element mounted on the 50 work support for projecting a ridge of fabric upwardly through the opening into needle penetrating position, normally inoperative means for severing the needle thread between the looper and the needle when the latter is at the beginning of its stroke, and means for rendering the severing means operative upon depression of the work support.
26. In a single thread blind stitch sewing machine, the combination with a frame, of a stationary presser foot mounted on said frame and having an opening therein, a stitch forming mechanism mounted on the frame above the foot and including a threaded needle mounted for reciprocations across the opening in said foot and a 55 cooperating non-threaded looper, a depressible work support mounted on the frame below the foot, a ridge forming element mounted on the work support for projecting a ridge of fabric upwardly through the opening into needle penetrating position, a thread clamp located between the 60 looper and the needle when the latter is at the beginning of its stroke, a thread cutting knife, normally inoperative means for first positioning the leg of the needle thread extending from the needle into the thread clamp and for subsequently moving said thread into severing relation with said knife at a point between the clamp and the fabric being stitched, and means for rendering said positioning and severing means effective upon depression of the work support.
27. In a single thread blind stitch sewing machine, the combination with a frame, of a stationary presser foot mounted on said frame and having an opening therein, a stitch forming mechanism mounted on the frame above the foot and including a threaded needle mounted for reciprocations across the opening in said foot and a cooperating non-threaded looper, a depressible work support mounted on the frame below the foot, a ridge forming element mounted on the work support for projecting a ridge of fabric upwardly through the opening into needle penetrating position, a thread clamp located between the looper and the needle when the latter is at the beginning of its forward stroke, normally inoperative means for first positioning the leg of the needle thread extending from the needle into the thread clamp and for subsequently moving said thread into severing relation with said knife at a point between the clamp and the fabric being stitched, and means for rendering said positioning and severing means effective upon depression of the work support.
28. In a blind stitch sewing machine, the combination with a frame including a standard and a laterally extending arm, of a horizontal presser foot fixed to the free end of said arm and having an opening, a stitch forming mechanism mounted on said arm above the foot and including a threaded needle mounted for reciprocations across the opening in the foot, a depressible work support mounted on the frame and located below said foot, a ridge forming element mounted on the work support for projecting a ridge of fabric upwardly through the opening into needle penetrating position, normally inoperative means for severing the needle thread above the foot, and means for rendering the severing means operative upon depression of the work support.
29. In a blind stitch sewing machine, the combination with a frame including a standard and a laterally extending arm, of a horizontal presser foot fixed to the free end of said arm and having an opening, a stitch forming mechanism mounted on said arm above the foot and including a threaded needle mounted for reciprocations across the opening in the foot, a pivoted work support mounted on the frame and located below said foot, a ridge forming element mounted on the work support for projecting a ridge of fabric upwardly through the opening into needle penetrating position, a stationary knife mounted on the arm above the foot, a normally inoperative carrier arm supported on the arm below the knife, and connections between the carrier arm and the work support for operating the former upon depression of the latter to elevate the needle thread into cutting relation with said knife.
30. In a blind stitch sewing machine, the combination with a frame including a standard and a laterally extending arm, of a horizontal presser foot fixed to the free end of said arm and having an opening, a stitch forming mechanism mounted on said arm above the foot and including a

threaded needle mounted for reciprocations across the opening in the foot, a pivoted work support mounted on the frame and located below said foot, a ridge forming element mounted on the work support for projecting a ridge of fabric upwardly through the opening into needle penetrating position, a stationary knife mounted on the arm above the foot, a horizontal rock shaft journaled on the presser foot, a thread carrier arm fixed to the rock shaft for elevating the needle thread into cutting relation with the knife, and means for operating the rock shaft upon depression of the work support.

31. In a blind stitch sewing machine, the combination with a frame including a standard and a laterally extending arm, of a horizontal presser foot fixed to the free end of said arm and having an opening, a stitch forming mechanism mounted on said arm above the foot and including a threaded needle mounted for reciprocations across the opening in the foot, a pivoted work support mounted on the frame and located below said foot, a ridge forming element mounted on the work support for projecting a ridge of fabric upwardly through the opening into needle penetrating position, a stationary knife mounted on the arm above the foot, a horizontal rock shaft journaled on the presser foot, a thread carrier arm fixed to the rock shaft for elevating the needle thread into cutting relation with the knife, and means for operating the rock shaft upon depression of the work support including a lever fulcrumed on the frame arm and an arm fixed to the work support for operating said lever.

32. In a blind stitch sewing machine, the combination with a frame including a standard and a laterally extending arm, of a horizontal presser foot fixed to the free end of said arm and having an opening, a stitch forming mechanism mounted on said arm above the foot and including a threaded needle mounted for reciprocations across the opening in the foot, a pivoted work support mounted on the frame and located below said foot, a ridge forming element mounted on the work support for projecting a ridge of fabric upwardly through the opening into needle penetrating position, a stationary knife mounted on the arm above the foot, a horizontal rock shaft journaled on the presser foot, a thread carrier arm fixed to the rock shaft for elevating the needle thread into cutting relation with the knife, means for yieldably retaining the carrier arm against upward movement, and means for oper-

ating the rock shaft against the tension of said yieldable means upon depression of the work support.

33. In a blind stitch sewing machine, the combination with a frame including a standard and a laterally extending arm, of a horizontal presser foot fixed to the free end of said arm and having an opening, a stitch forming mechanism mounted on said arm above the foot and including a threaded needle mounted for reciprocations across the opening in the foot, a depressible work support mounted on the frame and located below said foot, a ridge forming element mounted on the work support for projecting a ridge of fabric upwardly through the opening into needle penetrating position, a stationary knife mounted on the arm above the foot, a normally inoperative carrier arm supported on the arm below the knife, a thread clamp supported on the frame arm intermediate the knife and the carrier arm, and connections between the carrier arm and the work support for operating the former upon depression of the latter to elevate the needle thread first into the clamp and then into cutting relation with said knife.

34. In a single thread blind stitch sewing machine, the combination with a frame including a base, a standard, and an arm extending laterally from the upper end of the standard and terminating in a forwardly extending arm, of a horizontal presser foot fixed to the free end of the forwardly extending arm and having an opening therein, a work support pivoted on the base to swing about a horizontal axis in parallelism with the lateral arm and having a forwardly depressible portion located under the foot, said work support having a portion extending rearwardly of the pivot, a stitch forming mechanism mounted on the forwardly extending arm and including a threaded needle mounted for reciprocations across the presser foot opening and a co-operating non-threaded looper, a stationary knife mounted on said forwardly extending arm above the foot, a rock shaft journaled on the foot, a thread carrier arm fixed to the rock shaft for elevating the leg of the needle loop extending between the looper and the needle into cutting relation with said knife, and means for rocking said shaft upon depression of the work support including a lever fulcrumed on the forwardly extending arm and an arm fixed to the rear portion of the work support for operating said lever.

LOUIS G. BOWMAN.
